TRAY CONSTRUCTION

Samuel Saul, Jr., Pittsburgh, Pa.

Application February 24, 1943, Serial No. 476,885

3 Claims. (Cl. 220—1)

This invention is for a tray construction and relates to a tray of the type used in various industrial operations wherein the tray is designed to be removably supported on a rack.

This invention is especially adapted for use in connection with racks of the type disclosed in my copending application Serial No. 465,625, filed November 14, 1942, now Letters Patent No. 2,316,892, dated April 20, 1943, and the present invention may be considered as complementary to the one therein disclosed.

In various industrial plants racks are extensively used onto which may be hung trays, these trays being adapted to receive pieces of work which are being processed. The trays are ordinarily hung on the racks so as to project laterally from the racks. Several trays are usually placed on each rack. The trays may be brought to a particular station full of parts to be operated upon. The operator at that particular station may remove the parts from one tray, perform some machining operation and then transfer the parts to another tray. Trays may be moved about individually or frequently a whole rack is supported on a carriage so that several trays may be moved along with the rack from one place to another.

By reason of the nature of the work in connection with which these trays are used they are subject to abusive handling and to hard wear and rough treatment. In order to make them easy to handle they must be constructed of relatively light sheet metal. At the same time, many pounds and sometimes several hundred pounds may be loaded into a single tray. The purpose of the present invention is to provide a tray construction which may be conveniently placed upon the racks in connection with which they are to be used, which are relatively strong and which, at the same time, are relatively light. Also, according to the present invention, those portions of the tray which are adapted to engage the hooks on the supporting rack are formed to resist tearing of the metal and they are of such shape as to facilitate the placing of the trays upon the racks. Trays embodying my invention are designed to resist distortion or warping in use and to be more convenient to handle.

My invention may be more fully understood by reference to the accompanying drawings, in which:

Figure 1 is a front elevation of a rack with a tray embodying my invention thereon;

Figure 2 is a view partly in side elevation and partly in section and on a larger scale than Figure 1, showing the construction of the back wall of the tray and the manner in which the same is engaged on a supporting rack;

Figure 3 is a top plan view of the tray shown in Figure 2;

Figure 4 is an end view of the tray;

Figure 5 is a transverse vertical section on the plane of line V—V of Figure 3;

Figure 6 is a fragmentary view similar to Figure 5, showing a modified forward lip construction for the tray;

Figure 7 is a fragmentary view representing a section in the plane of line VII—VII of Figure 5, showing a detail of the handle construction at the end of the tray.

In the drawings, 2 designates a platform supported on casters 3 to enable it to be rolled about. This platform, as more fully shown and described in my copending application, is provided with an upwardly extending frame, the frame including parallel inclined racks 4. The racks are formed of angle iron with one web of each angle turned outward. This outwardly turned edge is provided with a series of equidistantly spaced notches 5, preferably of the form shown in Figure 2, forming intermediate hooks or fingers 6. These hooks or fingers are preferably of the shape fully shown and described in my copending application so as to have a maximum strength and to readily engage the trays but shaped to prevent accidental displacement of the tray due to the overloading of one end of the tray.

In the drawings I have shown but a single tray but it will be understood that several of the trays may be simultaneously used on a single rack. The present invention is directed more specifically to the structure of the tray which will now be described. As hereinbefore indicated, the trays are formed from a suitable gauge of sheet metal with a bottom 7, integral end walls 8, and a back wall 9. In the form of tray illustrated in Figures 1 to 5 inclusive, the tray is continuously open across the front, the bottom at the front of the tray having a specially formed lip which will be hereinafter more fully described. The sheet metal forming the back wall of the tray is, as most clearly shown in Figures 2 and 5, folded over upon itself to provide a double thickness of metal. This double thickness of metal is then folded down at a downwardly diverging angle, as indicated at 10. At each end of the tray the folded over portion 10 is bent inwardly against the back wall, as best shown at 11 in Figure 3, and these portions so pinched in are spot welded or tack welded to the back wall. Likewise, the portion 10 along the middle of the back wall is pressed in and spot welded, as indicated at 12. This formation thereby provides two elongated sockets or pockets 13 formed between the downwardly sloped part 10 and the back wall. Due to the metal being folded over to double thickness the upper part of the back wall 9 is reinforced with two thicknesses of metal, as indicated at 9a in Figure 2 and the part 10 is also of a double thickness of metal. This double thickness of metal reinforces the upper edge of the tray, makes it more resistant to bending or

warping and, at the same time, provides a structure which is resistant under all reasonable conditions of use to tearing or bending. As shown in Figure 2, the fingers 8 on the racks are adapted to be engaged under or projected into the pockets 13. Because of the relatively greater length of the pockets, it is easy for the operator to hook the tray into place on the rack, whereas it would be difficult if the pockets were of a shorter length such as to require the tray to be centered before it could be hooked into place. The double thickness of metal is a protection against the wearing of the pockets and, while the double thickness very materially increases the strength of the tray, the arrangement is such that the tray is not held out away from the rack 4 but, as shown in Figure 2, the lower rear corner of the tray bears against the front edge of the rack 4 so that any thrust due to the loading of the tray is resisted by the back wall being engaged against the rack.

To additionally strengthen the rear top edge of the tray along the region of the pockets, a longitudinally extending angle bar 14 is welded into the upper part of the tray with the vertical leg of the angle flush against and extending along the back wall 9 and with the horizontal web of the angle extending forwardly. A relatively light angle 14 thus welded in place renders the back of the tray structure quite rigid and prevents deformation of the pockets.

As shown in Figure 5, the forward edge of the bottom 7 is also formed of metal of double thickness flattened upon itself and formed down into a depending lip 15. The double thickness of metal forming this lip portion of the tray is further reinforced by a longitudinally extending angle bar 16 welded into place with the vertical web of the angle backing up the lip 15 and with the horizontal web of the angle bracing the forward edge of the bottom.

The tray as thus constructed is extremely rigid and capable of supporting heavy loads even though unequally placed upon the tray and the tray is highly resistant to abusive treatment and rough handling. In some cases the trays may function more in the nature of bins, in which case the forward edge of the tray is made as shown in Figure 6, while the rear wall is of the construction previously described. As shown in Figure 6, the metal forming the bottom 7 is carried forward to provide an upwardly extending wall 17 and the top edge of this wall is bent over as indicated at 18, to reinforce the edge.

To facilitate the handling of the tray there is a handle assembly designated generally as 19 on each end wall of the tray. This handle comprises a metal plate 20 having an outwardly bent ridge 21 intermediate its upper and lower edges, which plate is welded to the end wall of the tray. A looped handle 22 passes under the ridge portion 21 of the plate 20 so that the loop in effect is hinged to the end wall. The plate 20 has outwardly projecting fingers 23 at each end thereof over the ends of the loop. These fingers prevent the handles from folding up past a substantially horizontal position. This may be plainly seen in Figure 7. Because of this handle construction, the tray may be lifted without the handles folding upwardly against the end walls of the tray. Were they not stopped from swinging upwardly past a substantially horizontal position the fingers of the operator might be pinched when he undertook to lift a loaded tray.

While I have illustrated and described certain particular constructions, it will be understood that this is by way of illustration and that various changes and modifications may be made without the contemplation of my invention and under the scope of the following claims.

I claim:

1. For use on a rack structure having inclined tray supporting elements with a vertical series of notches providing hooks for engaging and supporting the trays, a tray structure formed of sheet metal with a bottom, end walls, and a back wall, the metal at the top of the back wall being folded over and flattened upon itself to provide a top portion of double thickness, the said portion of double thickness being outwardly folded upon itself and flattened down at each end and at the middle of the tray and being secured to the back wall of the tray where it is so flattened down, the portions intermediate the flattened down portions sloping downwardly and outwardly away from the back wall of the tray to provide elongated inverted hook engaging pockets.

2. For use on a rack structure having inclined tray supporting elements with a vertical series of notches providing hooks for engaging and supporting the trays, a tray structure formed of sheet metal with a bottom, end walls, and a back wall, the metal at the top of the back wall being folded over and flattened upon itself to provide a top portion of double thickness, the said portion of double thickness being outwardly folded upon itself and flattened down at each end and at the middle of the tray and being secured to the back wall of the tray where it is so flattened down, the portions intermediate the flattened down portions sloping downwardly and outwardly away from the back wall of the tray to provide elongated inverted hook engaging pockets, and an angle bar extending lengthwise along the upper edge of the back wall inside the tray with one leg thereof flat against the back wall and one leg projecting horizontally reinforcing the upper edge portion of the tray and serving to protect the tray from distortion when the tray is heavily loaded.

3. For use on a rack structure having inclined tray supporting elements with a vertical series of notches providing hooks for engaging and supporting the trays, a tray structure formed of sheet metal with a bottom, end walls, and a back wall, the metal at the top of the back wall being folded over and flattened upon itself to provide a top portion of double thickness, the said portion of double thickness being outwardly folded upon itself and flattened down at each end and at the middle of the tray and being secured to the back wall of the tray where it is so flattened down, the portions intermediate the flattened down portions sloping downwardly and outwardly away from the back wall of the tray to provide elongated inverted hook engaging pockets, and an angle bar extending lengthwise along the upper edge of the back wall inside the tray with one leg thereof flat against the back wall and one leg projecting horizontally reinforcing the upper edge portion of the tray and serving to protect the tray from distortion when the tray is heavily loaded, the tray being open along its front edge and having a downwardly turned lip thereon, and an inverted angle welded against the bottom of the tray and the back surface of said lip to prevent distortion of the lip of the tray.

SAMUEL SAUL, JR.
